FIRE HOSE NOZZLE

Peter Caird, Santa Rosa, Calif.

Application November 27, 1951, Serial No. 17,538

Term of patent 14 years

(Cl. D91—1)

To all whom it may concern:

Be it known that I, Peter Caird, a citizen of Scotland, residing at Santa Rosa, Sonoma County, State of California, have invented a new, original, and ornamental Design for Fire Hose Nozzle, of which the following is a specification, reference being had to the drawing, forming a part thereof.

Fig. 1 is a top plan view of a fire hose nozzle embodying my new design.

Fig. 2 is a side elevation, the far side being a duplicate thereof.

Fig. 3 is a side elevation taken at ninety degrees to Fig. 2, the far side being a duplicate thereof.

The dominant features of my design reside in those portions shown in full lines.

I claim:

The ornamental design for a fire hose nozzle, as shown and described.

PETER CAIRD.
